Fig. 4

Fig. 5

Fig. 6

Fig. 7

Fig. 8

FIG. 1 is a side elevation view of a farm wagon box showing my new design;

FIG. 2 is a side elevation view of the opposite side of FIG. 1;

FIG. 3 is a top plan view of FIG. 1;

FIG. 4 is a bottom plan view of FIG. 1;

FIG. 5 is a front elevational view of FIG. 1;

FIG. 6 is a rear elevational view of FIG. 1;

FIG. 7 is a perspective view as seen from the top and left of FIG. 1; and

FIG. 8 is a perspective view as seen from the bottom and right of FIG. 1.

I claim:

The ornamental design for a farm wagon box, substantially as shown.
